METHOD AND APPARATUS FOR BOTTLING

Evan L. Moberg, Latrobe, Pa., assignor to
McKenna Brass & Manufacturing Co., Inc.,
Pittsburgh, Pa., a corporation of Pennsylvania

Application March 6, 1933, Serial No. 659,867

11 Claims. (Cl. 226—115)

This invention relates to method and apparatus for bottling carbonated beverages and is herein particularly described as relating to filling machines for the bottling of carbonated beverages.

5 In modern filling machines for bottling carbonated beverages, provision is made for supplying an initial pressure—commonly termed the counterpressure—within the bottle prior to filling and for maintaining such pressure throughout the 10 filling operation. This counterpressure is maintained to prevent liberation of carbon dioxide gas from the charged water so that foaming of the bottled beverage may be obviated. The water tank and pressure reservoir in the bottling unit 15 is kept filled to a predetermined level with carbonated water. Gas under the same pressure as that of the charged water in the carbonator is stored above the water level and this stored body of gas serves as a reservoir for the counterpressure gas. As the bottle is filling with carbonated 20 water, the compressed gas with which it was filled, together with the air originally in the bottle, is returned to the water tank or filling tank. In order that the water level in the water tank 25 and pressure reservoir may be kept constant, it is customary to vent the gas displaced by carbonated water to the atmosphere. This results in a considerable wastage of the medium used to supply counterpressure. The carbonating unit supplies 30 the bottle filling machine with carbonated water under pressure. The gas required by the bottle filling unit must be under the same pressure as that under which the carbonated water from the carbonator is supplied to the water tank of the 35 filling machine.

As the carbon dioxide gas in the carbonator is under the same pressure as the carbonated water therein, it has hitherto been the practice, in machines of this character, to rely on carbon dioxide gas from the carbonating unit itself to supply this pressure in the bottling machine. A considerable portion of the relatively expensive CO₂ gas is wasted in the bottle filling operation in the filling unit, so it is a rather costly practice 45 to use carbon dioxide gas to supply the needed pressure.

I avoid this expense by using air to establish and maintain the pressure in the bottle filling machine. In order that the air may be supplied 50 at the same pressure as that exerted by the CO₂ gas in the carbonator, I regulate the air by means responsive to the gas pressure in the carbonator. By reason of this, I am enabled to use air in the bottling machine and avoid the waste of the 55 expensive carbon dioxide gas and at the same time control the air just as effectively as gas supplied from the carbonator has heretofore been controlled.

In the accompanying drawings, illustrating a 60 present preferred embodiment of the invention,

Figure 1 is a schematic view of the arrangement of the apparatus which includes a carbonating unit, an air compressor, a bottle filling machine, and a diaphragm valve;

Figure 2 is a plan view of a diaphragm valve through which the air pressure is regulated; and

Figure 3 is a cross-section of the diaphragm valve in the plane of III—III of Figure 2.

The bottling apparatus illustrated in Figure 1 comprises a carbonating unit C of any preferred or conventional design connected to a conventional or preferred type of bottling unit B through a pipe 2 in order that carbonated water may be supplied to the bottle filling machine B. In bottling machines of the type illustrated, gas under pressure is supplied to the connection 3 on the filling tank thereof. This gas is introduced into the empty bottle to build up a pressure therein before the carbonated water is introduced into the bottle, thereby preventing excessive foaming of the beverage in the filled bottle and the resulting loss in carbonation, all of which is well known to those skilled in the art. Heretofore, this gas has been carbon dioxide supplied directly from the carbonator C.

In the present invention, air instead of carbon dioxide gas is used in the bottling machine and for this purpose there is shown a source of air pressure A. This is shown as comprising a compressor 5 and a reservoir 6. Air under pressure is conducted from the reservoir through a pipe 7, diaphragm valve D and pipe 8 to the connection 3 on the bottle filling machine. In order that air pressure supplied to the pressure reservoir of the bottling machine may be definitely related to the pressure in the carbonator, the pressure regulator unit D is connected between the pipes 7 and 8 as shown.

The regulator unit comprises a diaphragm valve D (see Figures 2 and 3) which consists of a casting 9, in which is housed a diaphragm 10 and a valve 11. The diaphragm 10 is interposed between chambers 12 and 13 and is connected by means of a lever 14 to valve 11 so that movement of the diaphragm 10 is communicated to valve 11. The lever 14 is pivoted at 15 so that the moment arm of valve 11 about the pivot 15 is less than the moment arm of the diaphragm 10 about the pivot 15. By thus proportioning the moment arms, the force exerted on diaphragm 10 by the carbon dioxide gas from the carbonator through lever 14 against valve 11 is multiplied so that a comparatively small increase in pressure against diaphragm 10 will exert a larger force against the valve 11. This arrangement makes the valve 11 more sensitive. Chamber 12 is connected by means of pipe 16 to the carbonator unit. Thus, one side of the diaphragm is subjected to the pressure of carbon dioxide gas coming from the carbonating unit C by way of pipe 16. Valve 11

is contained within a valve chamber 17 which has at one end a valve seat 18 against which the valve is normally urged by means of the spring 19 interposed between the valve and the casing. Air under pressure is supplied from the air compressor unit A by means of pipe 7 which connects to the valve chamber at 20, this being the inlet side of the valve. The movement of valve 11 controls the admission of air to chamber 13. The chamber 13 has an outlet connection 21 to which the pipe 8 leading to the filling machine is connected.

When the CO₂ gas under pressure is admitted to chamber 12, diaphragm 10 moves outwardly toward chamber 13 and transmits its motion by means of lever 14 to the valve 11. Valve 11 is raised from its seat 18 and admits air under pressure from the supply pipe 7 into chamber 13 and thence through pipe 8 to the bottle filling machine. As soon as the air pressure in chamber 13 becomes equal to the pressure of the carbon dioxide gas in chamber 12, the diaphragm 10 will be in equilibrium and air at the same pressure as the CO₂ gas in chamber 12 will be supplied from the compressor A through pipe 7 to the chamber 13 and from thence through the pipe 8 to the bottle filling machine. If the air in chamber 13 reaches a pressure slightly greater than the pressure of the CO₂ gas in chamber 12, the diaphragm 10 will be forced outwardly from chamber 13 and valve 11 will be closed by the spring 19, thus shutting off the supply of air to chamber 13. As soon as the pressure in chamber 13 becomes less than the pressure of the carbon dioxide gas in chamber 12, valve 11 will be opened and air will be admitted to chamber 13. Thus, the air supplied to chamber 13 will be always kept at the same pressure as that of the carbon dioxide gas in chamber 12, which is the same pressure as the carbon dioxide gas in the carbonating unit C. Consequently, the pressure of the air supplied to the bottle filling machine through pipe 8 will always be the same as the pressure of the carbon dioxide gas in the carbonating unit.

It is thus evident that I have invented a novel device for supplying counterpressure in a bottle filling machine by using air controlled by the pressure in the carbonating unit instead of using carbon dioxide gas, thus enabling large savings to be effected by the operator of bottle filling apparatus.

While I have illustrated and described the present preferred form of my invention, it will be understood that it is not limited thereto but may be otherwise embodied and practiced within the scope of the following claims.

I claim:

1. The method of bottling, which comprises supplying air under pressure to a bottling machine, supplying carbonated water under pressure from a carbonating unit to the bottling machine, and varying the air supply directly in accordance with and proportionately to the variation of the pressure of gas in the carbonating unit.

2. The method of bottling, which comprises supplying fluid under pressure to a bottle filling machine, supplying carbonated water under pressure from a carbonating unit to the bottle filling machine, and regulating the fluid supply by the pressure of gas in the carbonating unit.

3. The combination with a bottling machine and a carbonating unit connected with the bottling machine for supplying carbonated water thereto, of means for supplying air under pressure to the bottling machine, and means re-

sponsive to gas pressure in the carbonator for controlling said first means.

4. The combination with a bottling machine and a carbonating unit connected with the bottling machine for supplying carbonated water thereto, of an air compressor for supplying air under pressure to the bottle filling machine, and a regulator responsive to the gas pressure in the carbonating unit for controlling the supply of compressed air to the bottle filling machine. 10

5. The combination with a bottling machine and a carbonating unit connected with the bottling machine for supplying carbonated water thereto, an air compressor connected with the filling machine, and a diaphragm valve responsive to the pressure of gas in the carbonating unit for controlling the supply of air under pressure to the bottle filling machine. 15

6. The combination with a bottling machine and a carbonating unit connected with the bottling machine for supplying carbonated water thereto, of means for supplying fluid under pressure to the bottling machine, and means responsive to the pressure of the gas in the carbonator for controlling the pressure of said fluid. 20

7. In combination, a machine for filling bottles with carbonated water under pressure, a carbonating unit connected to the filling machine for supplying carbonated water thereto, means connected with the filling machine for supplying fluid under pressure thereto, and means intermediate the fluid supply and the filling machine for directly varying the pressure of the fluid supplied to the filling machine in accordance with the variation of pressure of the 35 carbon dioxide gas in the carbonator.

8. In combination, a bottling machine, a carbonating unit connected with the bottling machine for supplying carbonated water thereto, means connected with the bottling machine for supplying fluid under pressure thereto, and means connected to the bottling machine, to the fluid pressure supply means, and to the carbonating unit and responsive to the gas pressure in the carbonating unit for regulating the pressure of the fluid supply to the bottling machine. 40

9. The combination of a bottling machine, a source of air supply connected to the bottling machine, a carbonator unit connected to the bottling machine for supplying carbonated water thereto, a pressure regulating valve with its outlet side connected to the bottling machine, and means for operating the valve comprising a diaphragm and means for conducting the gas pressure of the carbonator to one side of the 55 diaphragm.

10. The method of bottling, which comprises supplying to the bottle filling machine carbonated water under pressure from a supply unit, supplying air under pressure to the bottling machine, and regulating said air supply by the pressure of gas in the carbonated water supply unit. 60

11. In combination, a bottling machine, a carbonating unit connected to the bottling machine for supplying carbonated water thereto, an air compressor connected to the bottling machine for supplying air under pressure thereto, a pressure-responsive regulating valve connected between the air compressor and the bottling machine, said valve being operatively connected to the carbonating unit, whereby the gas pressure in the carbonating unit controls the operation of the regulating valve. 65
